UNITED STATES PATENT OFFICE

MICHELANGELO SUSI, OF NEW YORK, N. Y., ASSIGNOR TO GOLDSTEIN-WILKINS CORPORATION, OF NEW YORK, N. Y., A CORPORATION OF NEW YORK

DESIGN FOR A TEXTILE FABRIC

Application filed June 26, 1933. Serial No. 48,532. Term of patent 3½ years.

To all whom it may concern:

Be it known that I, MICHELANGELO SUSI, a citizen of United States residing at the city of New York, in the county of New York and State of New York, have invented a new, original, and ornamental Design for a Textile Fabric, of which the following is a specification, reference being had to the accompanying drawing, forming part thereof.

The figure is a plan view of a textile fabric showing my new design. A single unit of my design is substantially shown on the drawing.

I claim:

The ornamental design for a textile fabric, substantially as shown and described.

MICHELANGELO SUSI.
